UNITED STATES PATENT OFFICE.

CHARLES N. POLLOCK, OF CORINTH, MISSISSIPPI.

WRENCH.

988,142.

Specification of Letters Patent. Patented Mar. 28, 1911.

Application filed December 21, 1910. Serial No. 598,501.

To all whom it may concern:

Be it known that I, CHARLES N. POLLOCK, a citizen of the United States, residing at Corinth, in the county of Alcorn and State of Mississippi, have invented new and useful Improvements in Wrenches, of which the following is a specification.

The invention relates to a wrench, and more particularly to the class of quick adjusting wrenches.

The primary object of the invention is the provision of a wrench in which the adjusting screw may be entirely disengaged from the toothed rack on the shank of said wrench, whereby the movable jaw may be freely slid upon said shank for the quick adjustment of the movable jaw, so that subsequent thereto accurate adjustment may be had for the gripping of a nut or other part to be turned by the wrench.

Another object of the invention is the provision of a wrench in which its movable jaw may be freely slid on the shank of the wrench and accurately adjusted for the gripping of the work to be turned by the wrench.

A further object of the invention is the provision of a wrench in which a locking pin is arranged, whereby the adjusting screw may be engaged with and disengaged from the toothed rack on the shank of the wrench for the quick and accurate adjustment thereof.

A still further object of the invention is the provision of a wrench which is simple in construction, thoroughly reliable and efficient in operation, and inexpensive in manufacture.

With these and other objects in view, the invention consists in the construction, combination and arrangement of parts, as will be hereinafter more fully described, illustrated in the accompanying drawings, and pointed out in the claim hereunto appended.

In the drawings: Figure 1 is a side elevation of a wrench constructed in accordance with the invention. Fig. 2 is a similar view thereof, showing the adjusting screw disengaged from the rack teeth on the shank of the wrench. Fig. 3 is an edge view thereof. Fig. 4 is a sectional view on the line 4—4 of Fig. 1.

Similar reference characters indicate corresponding parts throughout the several views of the drawings.

Referring to the drawings by numerals, the wrench comprises a shank 5 terminating at one end in a stationary jaw 6, the opposite end being provided with a suitable handle 7 and this shank is channeled longitudinally on its opposite faces for lightness of construction, while maintaining the necessary strength in the direction in which the strains are transmitted thereto.

Provided at the inner edge of the shank are spaced obliquely disposed rack teeth 8 which are arranged thereon for a greater portion of the length of the shank to be engaged by adjusting means of a movable jaw, as will be hereinafter more fully described.

Surrounding the shank is a sleeve 9 which is adapted to be reciprocated upon the shank, the sleeve being formed with a movable jaw 10 to coöperate with the stationary jaw in gripping the work to be turned by the wrench. This sleeve 9 is formed with a longitudinal bore or guide way correspondingly shaped to the cross sectional area of the shank 5. Thus it will be seen that the said sleeve will be held securely against rotation or lateral movement upon the shank, during the traveling thereof on the same.

At a point medially of the length of the sleeve and opening through one longitudinal edge thereof is a recess 11, the same being intersected by a groove 12 which also opens through the edge of the sleeve through which the recess opens, the recess 11 being extended in the sleeve a sufficient distance to intersect the longitudinal bore or guide way in the said sleeve and within which is arranged an adjusting screw 13, the same containing a central bore in which is slidably fitted an axle pin 14, the latter being provided with an outwardly extending projection 15 working in the groove 12 and terminating in a finger knob or grip 16, the axle pin 14 being normally engaged in a socket 17 formed in the sleeve 9 and coinciding with the said socket 17 is a further socket 18 which is of less length than the said socket 17 and is disposed outside of the path thereof but opens into the same.

Within the groove 12 in the sleeve 9 is mounted a swinging block 19, the same being connected to the sleeve by means of the pivot 20 engaged therein and in the block, and this block 19 is formed with a central bore 21 opening through its inner end, the bore being extended for a greater portion of the length of the block, and in which is slid-

ably fitted the other end of the slideable axle pin 14, so that the said pin may be disengaged from the socket 17 and engaged in the socket 18, so that the adjusting screw 13 may be shifted out of engagement with the rack teeth 8 on the shank 5 of the wrench. It is of course to be understood that the normal position of the adjusting screw 13 is in engagement with the rack teeth 8 on the shank 10 of the wrench.

Within the bore 21 in the block 20 and working against the end of the axle pin 14 slideably fitted within the said bore is a coiled expansion spring 22 which serves to automatically move the axle pin 13 in a direction for positive engagement in either of the sockets 17 and 18 in the sleeve 9 slideably mounted on the shank of the wrench.

The finger grip or knob 16 is cut away to 20 form a notch 23, so as to permit the free sliding movement of the axle pin 14 within the bore 21 of the swinging block 19, when it is desired to disengage the adjusting screw 13 from the rack teeth 8 on the shank of the 25 wrench.

When the adjusting screw 13 is disengaged from the rack teeth on the shank 5, the sleeve 9 may be freely reciprocated thereon for the quick adjustment of the movable 30 jaw and thereafter the screw 13 may be engaged with the rack teeth for the accurate

adjustment of the movable jaw 10 for the positive gripping of the work to be turned by the wrench.

It is deemed needless to elaborate as to the 35 mode of operation of the wrench, as it is clearly apparent, and therefore a more extended explanation has been omitted.

What is claimed is:

A wrench of the class described, comprising 40 a shank having rack teeth in one edge and a stationary jaw at one end thereof, a sleeve slideably fitted on the shank and having a groove and recess in one edge, the said recess opening into the bore of the sleeve, a 45 swinging block pivotally mounted in the groove and having a bore therein, an axle pin slideably fitted in the bore, the said sleeve being formed with coincident varying lengthened sockets for receiving the pin, an 50 adjusting screw freely rotatable on the pin and normally engaging the rack teeth on the shank, and a finger knob projecting from the axle pin outside of the said groove in the sleeve.

In testimony whereof I affix my signature in presence of two witnesses.

CHARLES N. POLLOCK.
